UNITED STATES PATENT OFFICE.

FRANK FRANCE, OF FARGO, NORTH DAKOTA.

BRANDING-IRON.

SPECIFICATION forming part of Letters Patent No. 703,567, dated July 1, 1902.

Application filed August 26, 1901. Serial No. 73,249. (No model.)

To all whom it may concern:

Be it known that I, FRANK FRANCE, a citizen of the United States, residing at Fargo, in the county of Cass and State of North Dakota, have invented certain new and useful Improvements in Branding-Irons; and I do hereby declare the following to be a full, clear, and exact description of the invention, such as will enable others skilled in the art to which it appertains to make and use the same.

My invention has for its object to provide an improved branding device especially adapted for branding cattle or other live stock; and to this end it consists of the novel devices and combinations of devices hereinafter described, and defined in the claims.

The device in its preferred form is illustrated in the accompanying drawings, wherein like characters indicate like parts throughout the several views.

Figure 1 is a view, partly in side elevation and partly in vertical section, illustrating my improved branding device; and Fig. 2 is a view, principally in plan, but with some parts sectioned, showing the parts illustrated in Fig. 1.

The numeral 1 indicates the tank, the numeral 2 the handle, the numeral 3 the valved discharge-tip or burner, and the numeral 4 the flame-tube, of an ordinary hydrocarbon generator and burner, such as is used by tinsmiths, plumbers, and other mechanics.

The head of the branding device is of course of metal. It is preferably of oblong form, as indicated by the numeral 5, and is formed hollow and provided at its open end with a centrally-located hub portion 6, into which the projecting end of the flame-tube 4 is screwed to rigidly secure the said branding-head to the said tube. Openings 7 are thus left in the open end of the head 5 both above and below the hub 6, which flame-outlet passages 7 are adapted to direct the flame outward from the cavity within the head 5 after it has struck the bottom thereof and been deflected rearward. I find that the best results can usually be obtained by closing one or the other of the passages 7. In Fig. 1 the lower passage 7 is shown as closed by a removable frictionally-held cap or stopper 8, which is adapted to fit either one of said pas-

sages 7. The part of the branding-head which is to make the impression or brand-mark is indicated by the numeral 9. As shown in the drawings, this branding edge 9 is in the form of a straight rib. This straight rib for most brands is all that is required, as it may be used to form all such letters as "A," "H," "M," "N," "V," "W," "X," &c. However, the said branding-rib may be given various other forms, and the head 5 may be correspondingly varied. The said head, however, must be kept hollow and be directly secured to the flame-tube in position to receive the entire flame directly from the ends of the said flame-tube. To prevent too rapid radiation of heat through the sides of the heads 5, it is provided with an asbestos insulating-cover 10.

The complete device is adapted to be carried in one hand and to be operated by that hand. It is important to note that by means of the flame-tube 4 the flame is carried completely into the interior of the head 5 and is directed where it will produce the greatest heating effect on the portion 9.

What I claim, and desire to secure by Letters Patent of the United States, is as follows:

1. The combination with a burner of the character described, having a suitable hand-piece and provided with a projecting flame-tube 4, of the branding-head 5 having the centrally-located hub 6 and backturned flame-passage 7 located above said tube 4, the side walls of said head 5 being imperforate, substantially as described.

2. The combination with the burner of the character described having a suitable hand-piece and horizontally-projecting flame-tube 4, of the branding-head 5 having a centrally-located hub 6 and and backturned flame-passages 7 on opposite sides of said hub, and the removable cap or stopper 8 fitting both of the said passages 7 to close one or the other thereof, at will, said head 5 having imperforate side walls, substantially as described.

In testimony whereof I affix my signature in presence of two witnesses.

FRANK FRANCE.
